EXHAUST MANIFOLD

Clyde R. Eiss, Buffalo, and Frederick I. Steele,
Kenmore, N. Y., assignors to Curtiss-Wright
Corporation, a corporation of Delaware

Application October 10, 1941, Serial No. 414,432

5 Claims. (Cl. 60—29)

This invention relates to exhaust manifolding systems, particularly as applied to radial cylinder aircraft engines.

An object of the invention is to provide an exhaust pipe arrangement for radial cylinder engines whereby minimum exhaust back pressure is caused and wherein simplicity in manufacture is an important consideration. A further object is to provide a radial cylinder engine exhaust system wherein the exhaust is led to the atmosphere through a plurality of exhaust nozzles arranged in tandem, one of such exhaust nozzles serving not more than two of the engine cylinders. A further object of the invention is to provide an exhaust manifold system and exhaust nozzles therefor which are easy to assemble upon and to disassemble from an aircraft engine when installed in an aircraft.

Further objects of the invention will become apparent in reading the annexed description in connection with the drawings, in which:

Fig. 1 is a rear elevation of a radial engine exhaust pipe system;

Fig. 2 is a perspective view of an exhaust pipe and a nozzle therefor;

Fig. 3 is a front elevation of a pipe applied to an exhaust nozzle;

Fig. 4 is a side elevation of an exhaust system as applied to the lefthand side of a radial engine; and

Fig. 5 is a side elevation of an exhaust system as applied to the righthand side of a radial engine.

Single row radial cylinder engines having a four-stroke cycle normally comprise an odd number of cylinders, and a nine-cylinder engine has been chosen for illustration in Fig. 1. The cylinders are numbered from 11 to 19 in a clockwise direction, each cylinder having an exhaust port designated by the cylinder number primed. The firing order of an engine of this type is 11, 13, 15, 17, 19, 12, 14, 16, and 18, so that any two adjacent cylinders exhaust their products of combustion approximately one crankshaft revolution apart. In older type of manifolding, it was usual to interconnect four cylinders into a unit manifold on one side of the engine, and to interconnect the other five cylinders into a unit manifold on the other side of the engine, which manifolds were tapered from end to end to allow of adequate cross sectional area for the discharge of gases from the several cylinders, since the exhaust discharges from alternate cylinders overlapped. In other forms of older manifolds, all of the engine cylinders were sequentially con-

nected into a tapered manifold so that a single manifold outlet discharge the exhaust gas from all of the engine cylinders. Such tapered manifolds were expensive and somewhat difficult to construct and furthermore, were so bulky as to be difficult of application to an engine installation.

In the present system, we utilize a separate manifold for each pair of adjacent cylinders; for instance, cylinders 12 and 13 are served by a common manifold 21 of uniform diameter throughout its length, said manifold having its outlet end disposed at 22, near the side of the engine. Cylinders 14 and 15 are served by a manifold 23 of uniform diameter throughout its length, the outlet 24 thereof terminating in tandem relationship with the outlet 22 of the pipe 21. These two pipes 21 and 23 serve the four cylinders on the righthand side of the engine. A pipe 25, of uniform diameter, is connected to the exhaust ports of cylinders 11 and 19, such pipe having its outlet end disposed on the left side of the engine at 26. Cylinders 16 and 17 are served by a pipe 27 of uniform diameter throughout its length, having its outlet 28 disposed in tandem relation with respect to the outlet 26. The odd cylinder 18 is served by a single exhaust pipe 29 whose outlet 30 is also disposed in tandem relation with respect to the outlets 26 and 28. It will be seen that each exhaust pipe serves two adjacent cylinders and the exhaust discharges from such cylinders occur approximately one crankshaft revolution apart and therefore do not overlap. Thus, each pipe may be made with a diameter appropriate for the discharge of but a single cylinder and minimum back pressure will be attained.

On each side of the installation, is a brace member not secured to the engine mounting or cowling structure, the righthand brace member being numbered 32 and the lefthand brace member being numbered 33. The member 32 carries two exhaust nozzles 34 and 35 respectively connected to the exhaust pipes 23 and 21. The lefthand member 33 carries three nozzles 36, 37 and 38, respectively connected to the exhaust pipes 27, 25 and 29. These nozzles, as typically shown in Fig. 2, may be rearwardly directed to provide jet effect for the issuing exhaust gases and by the tandem arrangement of the several sets of nozzles, minimum aerodynamic drag results. These nozzles project beyond the profile of the engine cowling 40.

The several nozzles may be made as a unit assembly with their members 32 or 33 and as

shown in Fig. 3, the inner end of each nozzle comprises a receptacle 42 within which the end of the exhaust pipe such as 23 may be inserted, as shown in Fig. 3.

Where disassembly of the system is required, the cowling 40 is first removed. Thereafter, the members 32 and 33 may be removed as a unit with the exhaust nozzles, leaving the end of the several exhaust pipes free of any structural support. Thereafter, each pipe may be removed merely by detaching it from the cylinders which it serves. Preferably, a slip joint such as is shown at 44 is inserted in each exhaust pipe unit between the two cylinders which serves to allow for independent expansion and contraction of the engine cylinders and to avoid breakage of the exhaust pipe elements.

By the exhaust pipe system disclosed, a low drag, efficient exhaust nozzle system is provided analogous to that used on in-line engines. It has been found that the weight and bulk of the system disclosed compares favorably with the unitary manifold arrangements of the prior art.

While we have described our invention in detail in its present preferred embodiment, it will be obvious to those skilled in the art, after understanding our invention, that various changes and modifications may be made therein without departing from the spirit or scope thereof. We aim in the appended claims to cover all such modifications and changes.

We claim as our invention:

1. In combination with a multi-cylinder radial engine wherein the cylinders have an alternate firing order and wherein each cylinder has an exhaust port, an exhaust pipe for each pair of adjacent cylinders communicating with the exhaust ports thereof, the several pipes for the several pairs of cylinders being extended to lie in tandem relation at their outlet ends, and a member on opposite sides of the engine, each of said members having a plurality of tandem arranged exhaust nozzles with each one of which one of said pipes engages.

2. In combination with a multi-cylinder radial engine, the engine cylinders having an alternate firing order and each cylinder having an exhaust port, a plurality of exhaust pipes on each side of the engine each pipe communicating with the ports of not more than two adjacent cylinders,

the several pipes on each side of the engine having their outlet ends in tandem relation, a structural member on each side of the engine, and tandem arranged exhaust nozzles projecting outwardly from each member with each of which one of said pipes is connected.

3. In combination with a multi-cylinder radial engine, the engine cylinders having an alternate firing order and each cylinder having an exhaust port, a plurality of exhaust pipes on each side of the engine each pipe communicating with the ports of not more than two adjacent cylinders, the several pipes on each side of the engine having their outlet ends in tandem relation, cowling embracing said engine, and a unit assembly of tandem arranged exhaust nozzles projecting from said cowling with each of which one of said pipes is connected within the confines of said cowling.

4. In combination with a radial cylinder engine having an odd number of cylinders and alternate firing order, whereby adjacent cylinders exhaust nearly one crankshaft revolution apart, each cylinder having an exhaust port, a plurality of exhaust pipes each being connected to the exhaust ports of two only adjacent cylinders, whereby the flow of exhaust gas through each pipe is intermittent and substantially non-overlapping, said pipes being disposed around portions of the engine and having their outlet ends terminating at one side of the engine in tandem relation, and a unitary exhaust nozzle assembly comprising a plurality of tandem arranged nozzles with each one of which one said pipe is connected.

5. In an internal combustion engine having a plurality of radially arranged cylinders, said cylinders having an alternate firing order, a cowling embracing the engine, a plurality of exhaust pipes each connected to a pair of adjacent cylinders, and a pair of integral assemblies disposed on opposite sides of said engine and supported within and independently of said cowling, each assembly comprising a plurality of tandem disposed discharge nozzles extending through said cowling with each of said nozzles connected to and in communication with but one of said exhaust pipes.
